US00D964311S

(12) **United States Design Patent** (10) **Patent No.:** **US D964,311 S**
(45) **Date of Patent:** **** Sep. 20, 2022**

(54) **LOUDSPEAKER**

(71) Applicant: **Harman International Industries, Incorporated**, Northridge, CA (US)

(72) Inventors: **Kristopher Bellinghausen**, Whitmore Lake, MI (US); **David Dixon**, Livonia, MI (US); **Jeffery E. Fay**, Farmington Hills, MI (US); **Jose Tomas DeLuna**, Canton, MI (US); **Royce D. Channey**, Ann Arbor, MI (US)

(73) Assignee: **Harman International Industries, Incorporated**, Northridge, CA (US)

(**) Term: **15 Years**

(21) Appl. No.: **29/740,620**

(22) Filed: **Jul. 6, 2020**

(51) LOC (13) Cl. **14-01**

(52) U.S. Cl.

USPC **D14/204**

(58) **Field of Classification Search**

USPC D14/155–159, 160–173, 187–188, D14/189–198, 203.1–203.8, 204–216, D14/217–222, 225–229, 257–258, D14/400–416, 420, 426–431, 496, D14/900–902; D16/131–133, 135, D16/221–222, 227, 230–231, 234; D18/4.1–4.6; D21/324–332, 333, 403, D21/477, 512–513, 516, 566; D12/174–180

(57) **CLAIM**

The ornamental design for a loudspeaker, as shown and described.

DESCRIPTION

FIG. 1 is a top perspective view of a loudspeaker showing the new design;

FIG. 2 is a bottom perspective view thereof;

FIG. 3 is a front elevational view thereof;

FIG. 4 is a rear elevational view thereof;

FIG. 5 is a side elevational view thereof;

FIG. 6 is an opposite side elevational view thereof;

FIG. 7 is a top view thereof; and,

FIG. 8 is a bottom view thereof.

The broken lines in the figures illustrate portions of the loudspeaker that form no part of the claimed design.

1 Claim, 8 Drawing Sheets
